(57) **CLAIM**

The ornamental design for a line tying apparatus, as shown and described.

DESCRIPTION

FIG. 1 is a top, left side and front perspective view of a line tying apparatus in a closed configuration;

FIG. 2 is a bottom, left side and front perspective view of the line tying apparatus of FIG. 1;

FIG. 3 is a right side view of the line tying apparatus of FIG. 1;

FIG. 4 is a left side view of the line tying apparatus of FIG. 1;

FIG. 5 is a front view of the line tying apparatus of FIG. 1;

FIG. 6 is a back view of the line tying apparatus of FIG. 1;

FIG. 7 is a top view of the line tying apparatus of FIG. 1;

FIG. 8 is a bottom view of the line tying apparatus of FIG. 1;

FIG. 9 is a top, left side and front perspective view of the line tying apparatus in an open configuration.

FIG. 10 is a bottom, left side and front perspective view of the line tying apparatus of FIG. 9;

FIG. 11 is a right side view of the line tying apparatus of FIG. 9;

FIG. 12 is a left side view of the line tying apparatus of FIG. 9;

FIG. 13 is a front view of the line tying apparatus of FIG. 9;

FIG. 14 is a back view of the line tying apparatus of FIG. 9;

FIG. 15 is a top view of the line tying apparatus of FIG. 9;

and,

FIG. 16 is a bottom view of the line tying apparatus of FIG. 10.

The broken lines shown in the drawings illustrate portions of the line tying apparatus that form no part of the claimed design.

1 Claim, 14 Drawing Sheets
